UNITED STATES PATENT OFFICE.

OTTMAR H. LUTZ, OF ANN ARBOR, MICHIGAN.

JEWELER'S ANVIL.

SPECIFICATION forming part of Letters Patent No. 521,802, dated June 26, 1894.

Application filed April 13, 1893. Serial No. 470,162. (No model.)

To all whom it may concern:

Be it known that I, OTTMAR H. LUTZ, a citizen of the United States, residing at Ann Arbor, in the county of Washtenaw, State of Michigan, have invented certain new and useful Improvements in Jewelers' Anvils; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to new and useful improvements in jewelers' anvils, and consists in a certain construction and arrangement of parts as fully hereinafter set forth, the essential features of which being pointed out particularly in the claim.

In the ordinary construction of anvils of this class, they are provided with a rigid rectangular base, adapted to be clamped between the jaws of a bench-vise, which only enables the anvil to be secured in the vise with its projecting ends at right angles to the face of the jaws, or parallel therewith, and which requires said base to be entirely removed from said jaws, when it is desired to reverse the ends of the anvil.

To overcome these objections and provide an anvil that will greatly facilitate the work of the operator, is the object of this invention, which object is attained by the mechanism illustrated in the accompanying drawings, in which—

Figure 1 is a perspective view of my improved anvil clamped between the jaws of a bench-vise. Fig. 2 is a central vertical section through the anvil and jaws. Fig. 3 is a perspective view of the anvil and base, drawn apart.

Referring to the letters of reference, A designates the anvil proper, which is provided with the annular body portion B having the central depending stem C.

D designates the base having a central aperture d adapted to receive the stem C freely, and provided with an upper annular face b that coincides with the annular body of the anvil and upon which said body rests and is adapted to turn. Said base is split

diametrically as shown at a, the opening communicating with the central aperture and the adjacent walls of said opening standing some distance apart. The sides e of said base are flat and parallel, and afford a bearing for the jaws E of the vise, which are adapted to grasp said base, between the lower rectangular flange i, thereby said base may be securely retained in place by said jaws. The stem C of the anvil passes through the base, and its lower end is tapped, as shown at f in Fig. 3, to receive the screw h, by which means the anvil is swiveled to said base, but may be readily detached therefrom. With this construction it will be seen that, when the base D is resting freely between the jaws of the vise, the anvil is free to turn in either direction or into any position desired, and that when said jaws are tightened upon said slot-ted base, it will be compressed and firmly clamp the stem C, of the anvil, thus securing the anvil in any position to which it may be adjusted. If the operator is working upon one end of the anvil, and he desires to use the other, all that is necessary is to loosen the jaws and reverse the ends of the anvil, and again tighten the jaws, which is accomplished without removing the base from the jaws of the vise. This construction also enables the anvil to be set at any angle desired, whereby the work may be greatly facilitated.

Having thus fully set forth my invention, what I claim as new, and desire to secure by Letters Patent, is—

The combination with the vise, of the anvil provided with an annular body portion, the central stem depending from said body portion and having a tapped end, the compressible base having a central aperture that receives the stem of the anvil and a vertical slot opening into said aperture only, said base also having the upper and lower extending flanges embracing the opposite sides of said jaws, and the screw in the end of said stem extending onto said base.

In testimony whereof I affix my signature in presence of two witnesses.

OTTMAR H. LUTZ.
